INVENTOR

UNITED STATES PATENT OFFICE.

CHARLES BAUER, OF NEW YORK, N. Y.

NONBREAKABLE REFUSE CAN.

Application filed July 8, 1922. Serial No. 573,704.

To all whom it may concern:

Be it known that I, CHARLES BAUER, a citizen of the United States, residing at New York, in the county of New York and State 5 of New York, have invented certain new and useful Improvements in Nonbreakable Refuse Cans, of which the following is a specification.

This invention relates to cans used for 10 gathering refuse, and the main object is to provide a can having a bottom which is so constructed as to prevent breakage or denting when being handled.

Another object is to provide a modified 15 type of can in which the bottom is removable so that the latter may be readily replaced when required.

These and other objects will become apparent in the description below, in which 20 characters of reference refer to like-named parts in the drawing.

Referring briefly to the drawing, Figure 1 is a sectional elevational view thru the preferred type of can.

Figure 2 is a top plan view of the modified 25 type of can.

Figure 3 is a sectional elevational view of the modified type of can.

Figure 4 is an enlarged sectional elevational view of the lower portion of the modified type of can showing the means for releasing the bottom in open position.

Describing the drawing in detail, the 30 numeral 10 represents a relatively long annular shell which has reinforcing rings 11 attached to its upper and lower ends. The shell 10 is of the usual design common to refuse cans and has a loose-fitting cover 12 which has its edge 13 turned down in order 35 to protect said cover against bending or denting and also in order to provide a secure cover to prevent flies or the like from gaining access into the chamber 14. A handle 15, by which the cover 12 is removed, is secured centrally on said cover.

An annular bottom 16 having a convergent 40 wall 17 and an attachment rim 18 is secured to the shell 10 in such manner as to hang suspended with a space 19 between the bottom 16 and the lower edge 20 of the shell 10, said edge 20 being the base upon which the can stands.

The modified type of can is provided with a tapered internal ring 21 formed in the

lower portion of the shell 10, having a shoulder 22 on its underside.

A bottom member 23, having a convergent wall 24 similar to the bottom 16, is inserted into the shell 10 until the upper tapered edge 25 of said convergent wall abuts the shoulder 22.

The shell 10 is slotted vertically in a number of places, and between said slits are formed resilient catch pawls 26 which normally are aligned with the shell 10. Lips 27 formed at the free ends of pawls 26 are engageable with the flat flange 28, the latter being part of the bottom member 23. Swing arms 29 are secured to the resilient pawls 26 and normally project outwardly 70 therefrom.

In removing the bottom member 23 in the modified type of can, the swing arm 29 is urged toward the wall of shell 10. This operation pulls resilient pawls 26 outwardly 75 so that the face flange 28 becomes disengaged from the pawl lips 27 and the bottom 23 consequently drops out of place. Replacement is affected in the same manner that is, the shell 10 is inverted and a new bottom 80 member 23 is inserted into the shell until it rests upon the shoulder 22, after which the swing arms are released, the latter permitting resilient pawls 26 to return to their normal position and lock the bottom in place. 85

The usefulness of refuse cans of this type is obvious when considering the fact that cans are always handled in a rough way and consequently receive severe treatment. The usual practice is to lift a can to the 90 height of a wagon, to empty its contents, and then to allow it to fall to the pavement. Almost invariably the cans strike the pavement on the edge 20. This usually shears the rivets which secure the bottom to the can, or the shell wall may be bent inwardly or dented. The can herewith illustrated is designed to overcome such damage by having the bottom member provided with a convergent wall which is protected against 95 damage by the lower portion of the shell 10. It is apparent that the shell 10 may be dented or bent in falling without injuring the bottom.

I claim:—

A refuse can comprising an annular body shell, a removable cover therefor, an internal shoulder in said shell, a bottom member, a

flanged rim on said bottom, a convergent wall joining said flanged rim and bottom, said flanged rim adapted to be inserted into the body shell to engage said shoulder, ⁵ silent pawls formed integral with said shell and projecting thru slotted portions of said can, lips on said pawls adapted to normally

engage the flanged rim of said bottom, and swing arms secured to said pawls and adapted to release the latter from engagement with said flanged rim when removing said bottom member. ¹⁰

In witness whereof, I affix my signature.
CHARLES BAUER.
